UNITED STATES PATENT OFFICE.

THOMAS A. DALTON, OF HAZLETON, PENNSYLVANIA.

SHIP-PROTECTOR.

1,270,792.

Specification of Letters Patent.

Patented July 2, 1918.

Application filed July 26, 1917. Serial No. 183,001.

To all whom it may concern:

Be it known that I, THOMAS A. DALTON, a citizen of the United States, residing at Hazleton, in the county of Luzerne and 5 State of Pennsylvania, have invented certain new and useful Improvements in Ship-Protectors; and I do declare the following to be a full, clear, and exact description of the invention, such as will enable others 10 skilled in the art to which it appertains to make and use the same.

This invention relates to certain new and useful improvements in ship protectors.

One object of the invention is to provide 15 a torpedo guard for ships which may be moved out of the water when not in use to prevent the speed of the ship from being lessened, and which when in its raised position will serve in the capacity of a shield for 20 protecting the ship against shell fire.

Another object of the invention is to provide a torpedo guard for ships which is normally held out of the water and which is automatically released and lowered upon 25 the approach of a submarine, torpedo, or the like.

A further object of the invention is to provide a torpedo guard for ships which is movable in and out of the water and which 30 is provided with supporting means for holding the guard away from the sides of the ship when in use and permitting the guard to be swung close to the sides of the ship when in its raised position to not interfere 35 with the loading and unloading of the ship.

A further object of the invention is to provide a torpedo guard for ships which is made in sections so that in case one section becomes damaged it may be quickly and 40 easily repaired.

A still further object of the invention is to generally improve upon devices of this class by the provision of a comparatively simple, strong, durable and inexpensive construction, one which will be efficient and reliable in operation and well adapted to the purpose for which it is designed.

With these and other objects in view, the invention consists of certain novel features 50 of construction and the combination and arrangement of parts as will be hereinafter fully described and claimed.

In the accompanying drawings forming a part of the application and in which similar reference characters designate like parts throughout the several views,

Figure 1 is a side view of a ship showing a device constructed in accordance with this invention applied thereto and in raised position.

Fig. 2 is an enlarged face view of a portion of the guard.

Fig. 3 is a horizontal sectional view taken on the plane indicated by the line 3—3 of Fig. 2.

Fig. 4 is an enlarged transverse sectional view through a portion of the ship illustrating the device applied thereto and in raised position.

Fig. 5 is an enlarged face view of a portion of the guard, showing a portion of the side of the ship and the mechanism connected to the guard for raising the same out of the water.

Fig. 6 is a detail sectional view of a portion of the device.

Fig. 7 is a sectional view taken substantially on the line 7—7 of Fig. 6 and Fig. 8 is a diagrammatic view illustrating the mechanism for raising and holding the guard out of the water, and then automatically releasing the same and lowering it into the water.

In the embodiment illustrated the letter A designates a conventional form of ship. Revolubly mounted in suitable bearings 1 on each side of the ship A is a windlass shaft 2 upon which is fixed in any convenient manner a plurality of winding drums or windlasses 3. Arranged adjacent the windlasses 3 and securely fastened to the ship are brackets 4 having mounted thereon pulleys 5 and having lugs 6 projecting outwardly therefrom. The purpose of these parts is to be hereinafter more fully described.

The reference numeral 7 designates as a whole a guard or protector for the side of the ship. This guard or protector 7 extends substantially the entire length of the ship and is made up of comparatively narrow strips 8 of steel or the like. The guard is preferably made in sections so that in case a portion of it is damaged, only the section affected may require repair. These sections are shown as having their adjacent ends connected by transverse bars 9 of flat material, suitable bolts being passed through the ends of the various strips which comprise the sections and the bars.

Screwed to the guard 7 and disposed on the inner side or back face of the same is a

plurality of bars 10, the sides of said bars adjacent the guard being flat, while their other sides are concave as shown clearly by Fig. 7 of the drawings to properly receive 5 and be secured to tubular members 11. The lower ends of these members 11 are closed while their upper ends are provided with apertures. Disposed slidably within the members 11 and extending through the 10 aforesaid apertures in the upper ends thereof are rods 12. The upper ends of the rods 12 are pivotally connected to the lugs 6 carried by the brackets 4, while their lower ends are provided with a plurality of collars 13, 15 said collars fitting rather snugly within the tubular members 11 to prevent the rods 12 from wabbling in the same.

The members 11 are provided with slots 14 which extend longitudinally of the members 20 from the upper ends thereof to a point near their lower ends. Through these slots 14 extend lugs 15 which are secured to the rods 12 and which have pivotal connection with link members 16, the inner ends of 25 which are connected to blocks 17 which are slidably mounted in guide ways 18 to the sides of the ship.

From the above description, it will be seen that the guard or protector 7 is movable 30 in and out of the water, the tubular members 11 sliding upon the rods 12 until their upper ends engage the uppermost shoulder 13. The links 16 act in the capacity of braces for holding the guard away from the 35 side of the ship when the blocks 17 are in their lowermost positions in the guide ways 18.

Numerous ways may be employed for operating the windlass shaft 2 and raising the 40 guard out of the water, the guard being connected at its upper edge by cables 19 which are wound around the winding drums or windlasses 3. The means here shown consists of a plurality of electric motors 20 having pinions 21 fixed upon the one end of 45 their shafts which pinions mesh with gear wheels 22 fixed to the windlass shaft 2. It is to be here noted and understood that although two motors are shown and described, 50 yet this number may be increased and diminished as is found to be the most expedient in the particular case. In Fig. 8 of the drawings, where the invention is diagrammatically illustrated only one motor is 55 shown and this motor is included in the circuit 23 having a suitable source of current 24 therein and a switch 25 by which the motor is started and stopped. When operated, the motor will revolve in such a direction that the guard or structure 7 will be 60 raised out of the water.

The reference numeral 26 designates a relatively fixed clutch member. This clutch member 26 is positioned for engagement by 65 a rotatable clutch member 27 carried slid-

ably upon the shaft of the motor 20. A spring 28 surrounding the motor shaft and engaging the clutch member 27 holds the latter normally but yieldably in engagement with the clutch member 26 so that when the 70 motor has been operated to raise the torpedo guard, the latter will be locked in its raised position by the clutch.

In order to automatically release the means for holding the guard in its raised 75 position upon the approach of a torpedo, submarine or the like, a microphone 29 is employed. In the present instance, the microphone is disposed in the side of the ship in any suitable manner and is provided with 80 an indicating pointer 30 having a conducting member 31 which bridges a pair of contacts 32 carried by a portion of the casing of the microphone when the microphone is energized and the pointer is moved out of 85 its normal position. The contacts 32 are connected by conductors in a circuit 33 which includes a battery 34 and a solenoid 35.

Slidable within the solenoid 35 is a core 36, the outer end of which is connected to the 90 blade 37 of a switch 38 arranged in a circuit 39 having a battery 40 and a solenoid 41 therein. The solenoid 41 has a core 42 which is connected to a lever 43 fulcrumed intermediate of its ends and has one end in engagement with the slidable clutch member 27 of the motor shaft. When the solenoid 41 is energized and the core 42 drawn into the same, the lever 43 will be moved so as to move the clutch member 27 out of engagement with the clutch member 26. The means for holding the guard in its raised position thus being released, the guard will slide by gravity into the water, and when in this lowered position, it will protect the ship from 95 being struck by torpedoes, the links 16 holding the guard a considerable distance from the side of the ship so that if the torpedo is exploded when it contacts with the guard, the exploding will take place at such a distance from the ship as to not cause any 100 damage to the same.

Assuming that the guard is raised, and the microphone 29 is adjusted so as to operate when a torpedo or submarine approaches within a predetermined distance of the ship, upon the approach of such a torpedo or submarine the contacts 31 carried by the pointer of the microphone will engage the contact 32 and close the circuit 115 through the solenoid 35, this becoming energized will draw this core 36 inwardly and move the switch plate 37 into its closed position. The circuit of the solenoid 41 being thus closed, said solenoid will be energized, 120 and this will move the movable clutch member 27 out of engagement with the fixed member 26 and allow the guard to be released whence it will drop by gravity into 125 the water.

When it is desired to raise the guard out of the water, the switch 25 in the circuit 23 is closed and the motor will be caused to rotate, it being understood that the clutch member 27 is held out of engagement with the clutch member 26 while this is being done. A suitable latch 44 is employed to do this. This latch is to be engaged with the clutch member 27 when it is in its innermost position and prevents the spring 28 from forcing it into engagement with the member 26.

When the ship is docked and being loaded or unloaded it is preferable to have the guard 7 disposed rather close to the side of the ship so in order to provide for this, the manner in which the links 16 have their inner ends mounted in slide ways is devised. To cause the guard to move into close proximity with the side of the ship, the ears 45 carried by the blocks 17 are engaged by hooked rods or the like and the blocks are moved upwardly in the slide ways 18. Obviously, this may be done in other ways.

It is to be understood that other means for employing microphones may be used. It may be operatively connected to the means for holding the guard in its raised position in various ways, or it may even have no physical connection, with the mechanism but may be worn by a person who manually releases the holding means when he detects a torpedo or submarine approaching the vessel.

From the foregoing description, taken in connection with the accompanying drawings, the construction, use and operation of the device will be readily understood without a more extended explanation.

As various changes in form, proportion, and in the minor details of construction may be resorted to without departing from the spirit of this invention, it is to be understood that I do not wish to be limited to the construction herein shown and described other than as claimed.

I claim:

1. The combination with a ship; of a plurality of rods pivotally mounted at their upper ends to the side of the ship, a protector slidable upon said rods and movable in and out of the water, braces disposed between the lower ends of said rods and the side of the ship to hold said lower ends of said rods spaced from the latter, the outer ends of said braces being pivotally connected to said rods and their other ends slidably and pivotally connected to the side of the ship to permit them to fold into a vertical position to allow the protector to swing close to the side of said ship and means for raising said protector out of the water and holding it in raised position.

2. The combination with a ship; of a plurality of rods mounted upon the side of the ship, a protector movable into and out of the water, a plurality of tubular members extending across said protector and slidable on said rods, and means for raising said protector out of the water and holding it in raised position.

In testimony whereof I have hereunto set my hand in the presence of a subscribing witness.

THOMAS A. DALTON.
